FLOORING DEVICE

Brian T. Fudge, Blanco, Tex.

Application August 18, 1949, Serial No. 110,943

2 Claims. (Cl. 254—13)

1

This invention relates to article holding devices and more particularly pertains to a carpenter's tool of the type used in laying flooring, siding or the like that clamps to a sill or other suitable support and by which flooring is urged into the position to be nailed.

The primary object of the present invention is to provide a holder of this character that may be used to position boards on undersurfaces and vertical walls as well as top surfaces for nailing the same.

Another important object in accordance with the foregoing object is to provide a holder by which the boards to be secured are guidingly supported by the holders as they are urged into the desired position for assembly, and in which the supporting structure of the holder does not interfere with the nailing operation of boards having special features, such as tongue and groove joints.

Further objects are to provide a holder that will not slip from the supporting structure, and that will be simple and inexpensive in construction yet highly efficient for the purposes intended.

These, together with various ancillary objects and features of the invention which will later become apparent as the following description proceeds or attained by the present invention, a preferred embodiment of which has been illustrated by way of example only on the accompanying drawing wherein:

Figure 1 is a perspective view of the invention;

Figure 2 is a top plan view of the invention showing the same clamped to a sill and holding flooring in position to be nailed;

Figure 3 is a vertical sectional view of the invention taken substantially upon the plane of the section line 3—3 of Figure 2;

Figure 4 is an end elevational view of the invention, showing the same as applied in Figure 2 as from the left side of Figure 2, parts being shown in section; and,

Figure 5 is a vertical sectional view of the invention taken upon the plane of the section line 5—5 of Figure 1 and illustrates particularly the slide construction.

Reference is now made more specifically to the accompanying drawings, wherein like numerals designate similar parts throughout the various parts, and in which the numeral 10 indicates the carpenter tool generally.

The frame of the tool 10 is generally L-shaped and comprises a horizontal leg portion including a pair of horizontal, parallel angle irons 12, which are connected and spaced by a cross member or angle iron 14 to which they are welded or other-

2

wise secured. The L-shaped frame also includes a depending or vertical leg portion formed of legs 16 and 18 which depend from and are suitably secured to the angle iron 14. The frame members 12, 14, 16 and 18 are illustrated as being angle irons welded together, and this is the preferred construction as the materials are easy to obtain, and when welded together lend great strength to the frame.

10 The legs 14 and 18 are for the purpose of straddling a sill and are provided with means whereby a sill may be clamped securely therebetween. These means consist of a threaded bolt 20 which extends through and threadingly engages the leg 16 and an annular base 22 on the leg 16. The bolt 20 is provided with a handle 24, whereby the bolt 20 may be turned to force a sill 26 against the leg 18. The leg 18 is provided with an inturned spur or knife edge 28, which is adapted to penetrate the sill 26 upon the bolt 20 being tightened and thus act in conjunction with bolt 20 to hold the sill securely between the legs 16 and 18. The knife edge 28 is easily formed by bending an edge of the leg and sharpening it, and functions in a manner similar to the climbers used by linemen on wooden poles. This feature makes slipping of the legs 16 and 18 on a wooden sill 26 impossible.

The legs of each of the angles 12 constitute 30 guide bars 30 for the slide or clamping member 32. The slide 32 is the part of the tool 10 that is used to urge planks 34 into position for nailing to the sill 26. The slide 32 comprises an angle member having legs 36 and 38. As best shown in Figures 1, 3 and 5, a strip 40 having a down-turned flange 42 for an intermediate portion of the length of the strip 40 is suitably secured to the leg 36. The arrangement is such that slots 44 are formed in the slide 32 for slidably receiving the guide bars 30. Thus it will be seen that the slide is slidable on the guide bars 30 and is guided thereby.

To control the movement of the slide 32, a bracket 46 is secured to the slide 32 having an aperture 48. A threaded rod or bolt 50 threadingly extended through the angle iron 14, a boss 52 secured to the angle 14, and has a reduced inner end journaled in the bracket aperture 48. The bolt 50 being retained through the bracket 46 by a nut 54. The outer end of the bolt is preferably equipped with a conventional sliding handle 56 for enabling the operator to easily manipulate the bolt 50 in a cramped space to readily move the slide 32.

55 The strip 40 and the leg 36 are preferably

formed with registering apertures 58, through which nails may be readily driven or started into the very end or tongue 56 of planks 34 as may be seen in Figure 3. As the apertures 58 are spaced, they may be conveniently sized so as to constitute a guide for nails into the planks.

It will be readily appreciated that the tool may be used on an undersurface as well as top surfaces. In each case the cross member 14 and the leg 38 position the leg 36 so that a plank may be received between the sill and the leg 36 prior to the frame being clamped to the sill. It is to be noted that in working on ceilings or undersurfaces that after the tool 10 is clamped to a sill the guide bars 30 in conjunction with the leg 36 will support planks as the bolt is being tightened.

The operator may tighten the bolt 50 as tight as he desires, which is considerable when using warped lumber, without the tool 10 slipping on the sill because of the locking of the knife edge 28. From the foregoing, the construction and operation of the device will be readily understood and further explanation is believed to be unnecessary. However, since numerous modification and changes will readily occur to those skilled in the art after a consideration of the foregoing specification and the accompanying drawings, it is not desired to limit the invention to the exact construction shown and described, but all suitable modification and equivalents may be resorted to following within the scope of the appended claims.

Having described the invention, what is claimed as new is:

1. A flooring device for attachment to a flooring sill to position one piece of flooring against another on the sill, said device comprising a pair of horizontal laterally spaced angle irons overlapping the flooring, a transverse bar cross connecting corresponding ends of said angle irons and depending therefrom for slidably seating on the sill to hold said angle irons parallel with the flooring, a pair of legs depending from opposite ends of said transverse bar for straddling the sill, a clamping screw threaded through one of said legs and coacting with the other leg to clamp said sill therebetween for holding said angle irons stationary, an angle iron clamping bar slidably mounted at its ends on said angle irons transverse thereto for engaging over one edge of the piece of flooring to be positioned, and manipulative means operatively connected to said transverse bar and said clamping bar for sliding said clamping bar against the piece of flooring to be positioned.

2. A flooring device according to claim 1, said clamping bar having a center opening therein for driving nails therethrough into the piece of flooring when in position.

BRIAN T. FUDGE.
